UNITED STATES PATENT OFFICE

FRANK E. AURAND, OF CHICAGO, ILLINOIS

PORTABLE SURFACE CLEANING TOOL

Application filed March 28, 1930. Serial No. 439,574.

This invention relates to power driven devices for cleaning surfaces in general and more particularly for removing scale or the like from said surfaces. The instant invention may be characterized as an improvement upon the device disclosed in Patent No. 1,648,888 for portable surface cleaning tool granted to me November 15, 1927.

Prior to the introduction into the art of the device disclosed in the above noted patent, the usual method for removing scale, paint or the like, from surfaces involved the use of scrapers or chisels. The latter had been used in connection with pneumatically operated hammers for facilitating the work. Inasmuch as by the use of these devices, the maintenance of a constant pressure of the devices upon the surface being cleaned is difficult, serious damage results to the surface being cleaned when excessive pressure is inadvertently applied.

The introduction of the above noted patented device into the art facilitated the cleaning of surfaces in general and more particularly the removal of scale, paint or the like therefrom by the employment of a handy device having a power unit mounted thereon, together with a conveniently placed rotor driven by said unit and having a plurality of surface impinging or contacting elements distributed about the periphery of said rotor and adapted to contact with the surface being cleaned. The rotor employed consists of a plurality of axially disposed plates secured together by a plurality of angularly spaced axial pins arranged adjacent the periphery of said rotor and having mounted thereon a plurality of annular surface impinging elements. These elements are loosely mounted on the aforesaid pins and upon rotation of the rotor are adapted to be projected due to centrifugal force into contact with the surface adapted to be cleaned.

The instant invention relates to improvements upon said device. According to the present invention an adjustable depth controlling shoe is provided for the rotor carrying head of the device whereby the depth of impingement of the impinging elements is effectively controlled. This shoe provides for

the relative positioning of the rotor carrying head closer to or farther from the surface being cleaned so that the force with which the impinging elements are adapted to strike the surface acted upon may be varied to meet the depth requirements for effectively cleaning said surface. To facilitate the manipulation of the device in use, the operating movement of the device being toward and away from the operator, the shoe has been provided with anti-friction elements such for example, as rollers, whereby resistance to the reciprocating movement of the device is reduced to a minimum. The depth controlling shoe is also provided with a forwardly and upwardly inclined tip or nose, which acts as a carry-over means for the rotor carrying head where a rough or uneven surface having elevations and depressions therein due to crust or scale accumulations may be encountered.

Another feature of the instant invention is the provision of a rotor of novel construction. According to the present invention, the rotor includes a plurality of axially aligned discs provided with axial centrally disposed recesses secured together by angularly spaced axial pins arranged adjacent the periphery of said rotor and having mounted thereon a plurality of annular surface impinging elements and spacers in alternate and staggered relation.

In other words, those portions of the pins disposed between two adjacent discs carry thereon in alternate relation a surface impinging element and a spacer peripherally of the rotor. Those portions of the pins disposed in the adjacent space, carry spacing elements and surface impinging elements in like manner but where in the first space a pin carries a surface impinging element, the same pin carries a spacing element in the second space. The spacing elements are slightly larger than the thickness of the surface impinging elements giving the surface impinging elements a certain amount of axial play upon their respective pins so that upon projection thereof by centrifugal force as the rotor is rotated, the surface contacting peripheral portions of the surface impinging elements have a limited amount of lateral

play thus allowing these elements to operate upon the said surface upon that portion of said surface, which normally lies under the discs, whereby the entire surface underneath the rotor is effectively cleaned. The perforations provided in the discs for the accommodation of the axially extending pins are slightly larger than the pins so that in assembled condition, a limited amount of flexibility is provided to the rotor. In operative condition, the rotor is mounted on a spindle having a deformed periphery such for example, as may be provided by slabbing off portions of the spindle, so as to eliminate the employment of keys.

The axially disposed recesses provided in the discs of the rotor are made to conform to the periphery of the spindle. By the provision of the above noted limited amount of flexibility in the rotor, each of the discs as the rotor is axially mounted upon the spindle, readily accommodates itself to the spindle. This construction permits of the securement of an important advantage in assembling of the rotor heretofore unobtainable, and that is the elimination of otherwise requisite precision in assembly whereby the axially disposed perforations of the discs would have to be accurately aligned. As will be understood by those skilled in the art, the elimination of a step in assembly where great precision is required materially reduces the cost of manufacture. Then again, due to the flexibility of the rotor, each disc has rotational movement imparted thereto, whereas if the rotor were rigid, only the perfectly aligned discs would have such movement imparted thereto. Thus the strain is transmitted to all the discs directly instead of to some directly and others through the pins.

A further feature of importance resides in the provision of novel shock absorbing means for each of the surface impinging elements of the rotor. I have found in connection with my prior patented device hereinbefore referred to that due to the large number of impacts which the impinging elements necessarily receive with the rotor revolving at, for example, two thousand revolutions per minute, the rebound of each element after impact against its pin and subsequent impact thereagainst due to the centrifugal force causes the metal forming the element to gradually crystallize from its inner periphery to its outer, whereupon upon crystallization of the element it cannot hold together and bursts. This limits the life of an impinging element considerably, and of course, the efficiency of the rotor is minimized. In order to alleviate this condition and considerably increase the life of the rotor, I have provided a novel shock absorbing means for each of the impinging elements. To this end one or more coils of resilient wire in the na-

ture of bushings are loosely mounted on each pin between adjacent discs prior to the mounting of the impinging element thereon. Thus, as each impinging element rebounds after impact against the surface being cleaned, the reaction impact is considerably absorbed by the resilient wire shock absorbing element. I have found that the interpolation of such an element for each surface impinging element entirely eliminates crystallization of the impinging elements to the extent that the cutting peripheries of these elements wear out before any crystallization sets in. Actually, the useful life of a rotor is increased four-fold or more.

Another object of the present invention is the provision of a novel means for securing the rotor in assembled relation. To this end the pins passing through the discs and spacers are each provided at one end with an enlarged head for engaging the outer face of one end disc while at the other end each of the pins is provided with a transverse recess. After all the elements forming the rotor are assembled upon the pins, a length of wire is passed through the recesses at the ends of the pins and the ends of the wire are suitably bent to retain the wire in position. By the employment of this wire retaining means, it will be apparent that the assembly of the rotor may be simply and quickly accomplished.

Another important feature of the instant invention resides in the novel positioning of the securing means retaining the rotor on the spindle. To this end the outer end plates of the rotor are provided with enlarged perforations for the accommodation of the head of a headed element adapted to be threaded into the end of the spindle. By the provision of the enlarged perforations in the outer end discs, the head of the securing element engages the outer side of the next or second disc from the outer end, the securing element being thus normally seated within the outer face of the outer end disc and within the general outline of the rotor itself. This novel method of securing the rotor to the spindle permits me to secure an important advantage heretofore unattained, namely, that by the elimination of the projection of the spindle beyond the outer end of the rotor, the end of the rotor may be brought in close proximity to a wall or other upstanding element connected to the surface being cleaned whereby the rotor is effective for removing scale, paint or other like matter from the surface right up to the wall or other upstanding element connected with the surface being cleaned. In other words, this novel construction permits of the accessibility of the impinging elements of the rotor to otherwise inaccessible portions of the surface being cleaned. At the same time, this arrangement permits of the reversibility of the rotor end for end so that where two rotors

are employed and are mounted by sliding over opposite ends of a single shaft, and the tool is to be employed on continuous surfaces having no abrupt changes in contour, the necessity for "rights" and "lefts" is eliminated, as the rotor may be slipped onto the shaft of the tool from either side and the securing means will be confined within the outline of the rotor.

10 A still further feature of my invention is the provision of a novel impinging element comprising a pressed sheet metal member having radially disposed corrugations therein, thereby presenting an undulated periphery. It will be evident that in the employment of a tool of the character disclosed hereinafter for removing scale of substantial body or thickness, star wheels presenting jagged teeth would be best suitable inasmuch as the 15 surface therebeneath is relatively hard, being usually iron or steel. Where, however, the tool is employed to remove paint or other relatively soft accumulations from relatively soft surfaces, such as wood or artificial fiber 20 board, the penetrative effect of the rotor surface impinging elements must be materially reduced.

By the provision of a novel corrugated element presenting an undulated edge or periphery to the surface acted upon, the penetrative 30 effect of the impinging element is minimized to a degree where only the paint or like accumulation is effected simulating the action of a scraper without causing any injury to the 35 relatively soft surface being cleaned.

A further feature of the instant invention is the provision of another novel surface contacting or impinging element comprising a 40 wheel of relatively hard, non-brittle abrasive material having a hub in the nature of a sheet metal thimble. It will be apparent that by the employment of a rotor having elements of this character thereon, the contacting effect 45 upon the surface being cleaned will be in the nature of a fine scratching or abrasive effect of micrometric depth. The employment of a rotor provided with such elements is particularly advantageous where only a very thin film or crust of rust is being removed from 50 the surface being cleaned.

Other features of novelty and further advantages will appear from the following detailed description of a preferred embodiment 55 of my invention illustrated in the accompanying drawings in which:—

Figure 1 is a longitudinal elevational view showing a device embodying this invention with parts thereof in section;

60 Figure 2 is a cross-sectional view taken along the line 2—2 of Figure 1 and showing parts in elevation;

Figure 3 is a fragmentary view partly in section, the sectional portion of such view being along the line 3—3 of Figure 2;

65 Figure 3A is an inner end view of the rotor;

Figure 4 is a perspective view of the adjustable depth controlling shoe;

Figure 5 is an elevation of a modified form of surface impinging element;

Figure 6 is an edge view of the element 70 shown in Figure 5;

Figure 7 is an elevation of another modified form of surface impinging element; and

Figure 8 is a cross-sectional view of the element shown in Figure 7. 75

Referring more particularly to the drawings, a motor housing 9 having a suitable motor therein, is provided with a suitable handle 10 at its rear end. It will be understood that when the device is to be used for 80 cleaning surfaces where electrical energy is available for the operation of the device, the housing 9 may contain an electric motor for the operation of the device. Where, however, electrical energy is not available, the housing 85 9 may contain a pneumatically operated motor which may be suitably connected with a tank of an air compressor unit of any portable type which is now in extensive use.

A removable neck 11 extends from the 90 forward end of the motor housing 9 and is provided with an enlarged head 12 at the forward end thereof. The lower portion of the head 12 is preferably of the shape shown in Figure 3 in profile with the axis thereof 95 disposed perpendicularly to the axis of the housing and neck. A drive shaft 13 is mounted longitudinally in the neck 11 with the rear end thereof extending beyond the rear portion of the neck and being seated in 100 the inner race 14 of a roller bearing 15, the outer race 16 of which is seated in the bore of a boss 17 provided in a removable motor housing end plate 18. This removable end plate 18 may be interchangeably attached to 105 either an electric motor housing or to a compressed air motor housing, as desired. The rear end of roller bearing 15 above a washer 19 seated in the rear end of the bore of boss 17, the washer being of soft leather 110 or any other suitable material to prevent rearward passage of a lubricant which may be applied to the roller bearing through a lubricant conveying passage 9' into the housing 9. Bearing 15 is retained in the bore of 115 the boss 17 by means of a split resilient ring 20 seated in an annual groove 21 provided in the periphery of the bore. A fan 22 is splined in the rear end of drive shaft 13 so as to be disposed within the housing 9 and is suitably secured to said shaft. Shaft 13 120 may be suitably clutched or otherwise suitably connected with an armature shaft of an electric motor mounted in the housing 9 in the event such a motor is employed where electricity is available or may be clutched or otherwise suitably connected with the drive shaft of a pneumatic motor where the device is adapted to be driven from an air 125 compressor unit. A cover plate 23 is pro-

130

vided for the forward end of the boss 17 and has a bushing 24 embracing shaft 13 disposed axially therethrough. The forward end of the shaft 13 is provided with a reduced portion 25 supported in the inner race of a roller bearing 26, the outer race of which is seated in a bushing 27 at the forward end of the neck 11 in the upper rear portion of the head 12. The forward end of the shaft 13 is provided with a further reduced portion to which a worm 28 is splined and suitably spaced from the roller bearing 26 by means of a bushing 29, the head 12 being provided with an enlarged recess 30 for the accommodation of such worm. A nut 31 is threaded upon the extreme forward end of the shaft 13 in abutment with the outer end of the worm 28 to positively retain the worm on the shaft.

20 The head 12 is machined axially to provide a bore 32 disposed transversely with respect to the longitudinal axis of the neck 11. A spindle 33 is disposed axially within the bore 32 and carries a worm wheel 34 disposed centrally thereof with its teeth in engagement with the teeth of worm 28. Two end plates 35 and 36 are seated in the ends of the bore 32 and are suitably secured to the head 12 with their stop flanges 37 and 38, respectively, in abutment with the respective ends of the head 12. Plate 35 is provided with an axial bore 39 through which the spindle 33 extends and a split ring 40 is seated in a peripheral groove 41 in this bore snugly embracing the spindle 33. At its inner end, the plate 35 is provided with an enlarged axial bore 42 in which a roller bearing 43 is mounted with the inner race thereof embracing the spindle 33 and having its inner end in abutment with the hub 44 of worm wheel 34. A suitable spacing washer 45 may be positioned between the outer end of the bearing 43 and the inner face of the bore 42, the washer being of any resilient material to prevent end play of the bearing 43 along the spindle 33 in the direction of the plate 35. Plate 36, which is disposed on the other end of the hub 44 of the skew gear 34, is likewise provided with a ring 46, roller bearing 47, and washer 48. Beyond the plates 35 and 36, each end portion of the spindle 33 may be of any desired irregular contour and I have chosen as an example thereof to provide the spindle with two parallel, opposed faces 49.

50 The lower periphery of the head 12 is provided with a forwardly extending depression 50 and is slabbed off at its rear side to form a substantially flat face 51.

60 Referring particularly to Figures 1 and 4, an adjustable depth controlling shoe 52 having a rear flat portion 53 is adapted to be mounted for sliding movement along the face 51 of the head 12 with its forwardly extending and upwardly curved portion 54 being

adapted to be moved in and out of the depression 50. The flat portion 53 of the shoe 52 is provided with a centrally disposed longitudinal recess 55 through which a securing member 56 may pass for threading engagement with the head 12 to adjustably retain the shoe 52 on said head. Any well known expedient may be employed to prevent the shoe 52 from having movement other than sliding movement along the face 51, such for example as a tongue and groove connection, a dove tail connection, two such securing members as 56 may be employed or any one or more of a number of such well known expedients. At the juncture of the portions 53 and 54, the shoe is provided with two parallel longitudinally extending slots 57 in which two rollers 58 journaled upon a transversely extending pin 59 are positioned. As shown in Figure 1, the head 12 is provided with a depression 60 to accommodate the rollers 58 when the shoe 52 is in its uppermost adjusted position. The curved portion 54 will effectively carry the head 12 over a rough or uneven surface having depressions or sharp elevations therein.

Spindle 33 extends outwardly on either side of the head 12 and rotors generally indicated at 61 are adapted to be mounted upon these extended portions. Each rotor comprises a plurality of coaxially disposed spaced discs 62 connected together by a plurality of angularly spaced pins 63 arranged adjacent the peripheries of said discs. Mounted on the pins 63 in the spaces between the discs 62 in alternate relation peripherally of the rotor are a plurality of annular surface impinging elements 64 and spacers 65. For operating upon heavy scale, the surface impinging elements may comprise annular cutting members, the outer peripheries of which are provided with a plurality of integral jagged teeth 66 so that when they are projected into contact with such scale on the surface desired to be cleaned, they will act to break or chip the scale. The internal diameter of each of the elements 64 is considerably greater than the diameter of the pins 63 on which said elements are mounted. Thus, when the spindle 33 is rotated at a rapid rate, the elements 64 will by centrifugal force be projected outwardly. To prevent crystallization of the impinging elements 64 due to rebound reaction against the pins 63 resulting from the relatively large number of revolutions the rotors make and the resultant large number of impacts against the surface being cleaned, one or more coils of wire 63' in the nature of bushings are loosely mounted upon the pins 63 between the pins and inner peripheries of the impinging elements. Thus as each impinging element rebounds after impact with the surface being cleaned, the reaction impact against the corresponding pin is considerably absorbed by the bushing entirely.

eliminating crystallization of the impinging elements and thereby considerably increasing the effective life of such elements.

The axial recesses or perforations of each 5 of the discs 62, excepting those of the end discs 62' indicated at 62a, are of a shape conforming to the outer periphery of the spindle 33. The perforations provided in the plates or discs 62 for the passage therethrough of 10 pins 63 are slightly larger than the diameter of the pins 63, so that when the pins are secured against displacement by the passage through the ends thereof of a common securing wire element 64' (see Figure 3A), the 15 rotor will have a limited amount of flexibility in assembled condition. Thus, when the rotor is to be mounted upon the spindle 33 as the discs 62 are progressively slid upon the spindle 33, the discs will automatically align and 20 adjust themselves to the outer periphery of the spindle 33. This permits of the elimination of assembly work involved in the assembling of the rotors requiring utmost precision were the rotors to be of a rigid structure. In 25 addition, it is to be noted that due to the limited amount of flexibility provided in the rotors, rotational movement is transmitted to each of the discs instead of just to one or a few of the discs if the rotor structure were 30 rigid and the axial perforations were not in perfect alignment.

The outwardly extending ends of the spindle 33 are somewhat shorter than the normal length of the rotors 61 and each end is provided with an internally threaded axial recess for the accommodation therein of a headed securing member 67. Referring particularly to Figure 2, it will be noted that the central perforations 62a of the end discs 62' are circular in shape, the diameter of this perforation being slightly larger than the diameter of the head 68 of the securing member 67. Thus, after the rotor has been mounted upon the spindle 33 and the securing member 67 45 is threaded into the end of the spindle, the head 68 thereof passes through the perforation 62a in the end disc 62' and engages the outer face of the second disc 62 to retain the rotor upon the spindle. In seated position, 50 the head 68 of the securing member 67 is seated entirely within the end plane of the rotor, thus eliminating any projection of the spindle beyond the outer end of the rotor.

The surface impinging elements 64 are 55 thinner than the space between the adjacent discs 62, as defined by the spacing elements 65, so that the elements 64 have a limited amount of lateral play upon the pins 63. As the elements 64 are projected outwardly by 60 centrifugal force, the lateral play thereof upon the pins 63 permits these elements to operate upon a space between adjacent spaces below the discs 62, thus rendering the elements 64 effective upon the entire surface 65 underneath each rotor rather than only upon

spaces of the surface lying exactly underneath the spaces between the discs 62.

A suitable shoulder 69 is provided integrally with the upper portion of the head 12 and is adapted through means of screws 70 to support a semi-cylindrical guard 71 above the rotors and concentric therewith to prevent flying scale or other like matter from being thrown upwardly and rearwardly of the head 12 thereby offering protection from 75 such flying scale or other matter to the operator of the device.

A knob 72 is suitably secured to the upper side of the head 12 for purposes of providing a convenient hand hold for the operator to 80 guide the forward end of the tool and to provide a means whereby the operator may exert a downward pressure upon the forward end of the device to restrain this end of the device from being lifted off the surface being 85 cleaned due to the reaction of the impinging elements 64 resulting from the impacts of these elements upon said surface.

In Figures 5 and 6, I have illustrated a modified form of surface impinging element 90 comprising a sheet metal disc 73 provided with radial corrugations or striations 74 presenting an undulated edge or periphery 75 which may be provided in a rotor of a character similar to those disclosed in Figures 2 95 and 3 for purposes of operating upon a relatively soft surface. It will be apparent that with this type of surface impinging element, the normal cutting depth is materially reduced so that the device may be readily employed for removing accumulations such as 100 paint, varnish, or the like, from wood surfaces.

For purposes of operating upon a surface where only a scratching or abrasive effect is desired, as in the case of removing a relatively thin surface formation of rust or like substance, I have provided a further modified form of surface impinging element, shown in Figures 7 and 8. This element 105 comprises an annular member of abrasive material 76 having a hub or thimble 77 of pressed sheet metal extending through the central perforation thereof with the ends of said thimble being stamped, swaged, or spun back toward the flat faces of the element. It will be, of course, understood that the abrasive substance must be such as to be hard, yet not brittle, so that the impact imparted thereto as it impinges upon the contacting surface will not rupture the element. 110

Due to the novel characteristics of the rotors disclosed herein, it will be evident that the rotors may be quickly and cheaply assembled and may be quickly replaced upon the spindle of the device.

It will be obvious to those skilled in the art that by reason of the provision of the rotor and the surface impinging elements thereon, the speed at which said rotor may 115

be driven and the ease with which the device may be manipulated that surfaces having accumulations of scale or the like thereon may be quickly and conveniently cleared of such scale. By the provision of an adjustable depth controlling shoe, the depth of surface cut may be regulated with ease to operate upon surfaces of almost any thickness of scale. By the provision of the novel 10 curing means for the rotors whereby the securing means is disposed within the rotor and within the plane of the outer disc of said rotor, the tool is effective for cleaning scale or other accumulations from surfaces along 15 the edge of a surface defined by an upstanding wall or other upright joined with said surface.

While I have shown a preferred embodiment of my invention, I do not wish to be limited thereto inasmuch as certain changes may be made therein without departing from the essence of the invention. Among these changes may be the employment of some other means for the securement of adjustability of the shoe 52 and the curved portion 54 thereof may be provided with additional rollers for reducing friction between the underside of said curved portion when it is carrying out its carry-over function; while 20 I have disclosed a device wherein two rotors are employed, a single one or more than two may be employed; and other modified forms of impinging elements may be provided in the rotors.

35 As will be understood by those skilled in the art other changes may be made and many details of construction varied without departing from the spirit and scope of the appended claims.

40 What I claim and desire to secure by Letters Patent is:

1. In a device of the character described, a rotor including a plurality of coaxially disposed discs, pins secured through said discs and spaced apart circumferentially of said 45 rotor, spacers on said pins between said discs, and annular movable elements disposed between said discs, said spacers and elements being mounted on said pins in staggered circumferential relation.

50 2. In a device of the character described, a rotor including a plurality of coaxially disposed discs, pins secured through said discs and spaced apart circumferentially of said 55 rotor, and spacers and annular movable elements on said pins between said discs, said spacers maintaining said discs in spaced apart relation forming spacing wider than the thickness of said elements whereby said elements have lateral play on said pins.

55 3. In a device of the character described, a rotor including a plurality of coaxially disposed discs, pins secured through said discs and spaced apart circumferentially of said 60 rotor, and spacers and annular movable ele-

ments on said pins between said discs, said discs having relative movement on said pins whereby the rotor has a limited amount of flexibility.

4. In a device of the character described, a 70 rotor adapted to be mounted on a spindle having a deformed periphery and including a plurality of coaxially disposed discs having axial recesses conforming to the periphery of said spindle, pins secured through said discs and spaced apart circumferentially of said 75 rotor, and spacers and annular movable elements on said pins between said discs, said discs having relative movement on said pins whereby said rotor has a limited amount of flexibility, so that said discs may adjust themselves on said spindle when said rotor is axially mounted on said spindle.

5. In a device of the character described, a 80 rotor adapted to be mounted on a spindle having a deformed periphery and including a plurality of coaxially disposed discs having axial recesses conforming to the periphery of said spindle, pins secured through said discs and spaced apart circumferentially of said 85 rotor, and spacers and annular movable elements on said pins between said discs, said discs having relative movement on said pins whereby said rotor has a limited amount of flexibility, so that said discs may adjust themselves on said spindle when said rotor is axially mounted on said spindle, said spacers maintaining said discs in spaced apart relation forming spaces therebetween wider than 90 the thickness of said elements whereby said elements have lateral play on said pins.

6. In a device of the character described, the combination with a spindle, of a rotor comprising a plurality of coaxially disposed discs having axial recesses to conform to the periphery of said spindle, the recess of one of said discs being enlarged, and a headed element adapted to secure said rotor to said spindle and adapted to be received in said enlarged recess whereby the head of said 100 headed element will be disposed within the outer plane of said disc.

7. In a device of the character described, a rotor comprising a body portion, a journal member carried by said body portion, an annular member movable relative to said journal member and a shock absorbing medium interposed between said journal member and said element.

8. In a device of the character described, a rotor comprising a body portion, a journal member carried by said body portion, an annular member movable relative to said journal member and a loosely mounted bushing carried by said journal member and disposed between said member and said element to absorb shock incident to impact of said element against said member.

9. In a device of the character described, a 120 rotor comprising a body portion, a journal member carried by said body portion, an annular member movable relative to said journal member and a loosely mounted bushing carried by said journal member and disposed between said member and said element to absorb shock incident to impact of said element against said member.

member carried by said body portion, an annular member movable relative to said journal member and a loosely mounted resilient bushing carried by said journal member and disposed between said member and said element to absorb shock incident to impact of said element against said member.

10. In a device of the character described, a rotor including a plurality of coaxially disposed discs, pins extending through said discs in circumferentially spaced relation, spacers between adjacent discs, annular movable members disposed between adjacent discs, said spacers and members being mounted on 15 said pins in staggered circumferential relation, and loosely mounted resilient bushings on said pins between said pins and members.

11. In a device of the character described, a rotor comprising a plurality of coaxially disposed discs, pins extending through said discs in circumferentially spaced relation, means cooperating with said discs to maintain them in spaced relation, annular movable members carried by said pins in the 25 spaces between the discs, said members being arranged in staggered circumferential relation, and loosely mounted resilient bushings on said pins and cooperating with corresponding members to cushion impacts between said pins and corresponding associated members.

In witness whereof, I hereunto subscribe my name this 24th day of March, 1929.

FRANK E. AURAND.
